Attorney.

UNITED STATES PATENT OFFICE.

JAMES E. RASOR, OF SHERMAN, TEXAS.

VULCANIZING APPARATUS.

1,305,468.

Specification of Letters Patent. Patented June 3, 1919.

Application filed July 12, 1918. Serial No. 244,592.

To all whom it may concern:

Be it known that I, JAMES E. RASOR, a citizen of the United States, residing at Sherman, in the county of Grayson and State of Texas, have invented certain new and useful Improvements in Vulcanizing Apparatus, of which the following is a specification.

My invention appertains to tire retreading apparatus, and aims to provide a novel and improved vulcanizer for rubber tire patches.

It is the object of this invention to provide an apparatus adapted to be employed in vulcanizing rubber tire patches and the like, or for divers other purposes, which shall be comparatively simple, durable, and inexpensive in its construction, as well as being practical and efficient in operation.

With the foregoing and other objects in view which will appear as the description proceeds, the invention resides in the combination and arrangement of parts and in the details of construction hereinafter described and claimed; it being understood that changes in the precise embodiment of the invention as herein disclosed can be made within the scope of what is claimed without departing from the spirit of the invention.

The invention has been illustrated more or less diagrammatically in its preferred embodiment in the drawing accompanying this application which forms a part thereof, and wherein:

Figure 1, is a side elevation of the device. Fig. 2 is a plan view of the same with the lid removed and Fig. 3 is a sectional elevation on about line X X of Fig. 2.

Referring to the numerals of reference employed to designate corresponding parts throughout the several views, the vulcanizing chamber of my apparatus comprises concentric outer and inner shells 1 and 2 of any desired cross sectional contour, defining an intermediate chamber 3 that is filled with heat non conducting material. The bottom 4 of the chamber is secured to the outer shell 1 in the usual manner and a transverse partition 5 is located a suitable distance above it to define an intermediate space 6 that is also filled with a non conductor of heat.

A suitable steam boiler 7, having the usual fittings,—not shown, is provided, from which extends an upstanding steam pipe 8, the

other end of the said pipe having an elbow 9 attached thereto. Attached to the elbow 55 9 is a laterally disposed pipe 10 which enters the top of the apparatus and is then formed into a horizontally disposed series of heating coils 11, disposed around the inner shell 2 of the same. The series of 60 coils 11 incline downward to the partition 5 where the lower end is attached to a discharge pipe 12 that enters the side of the boiler.

Centrally located in the chamber and of the same height as the shells 1 and 2, is an upstanding tube 13; it is secured to the partition 5 and exteriorly of its outer surface, and adjacent thereto, is a series of pipe coils 14, similar to the coils 11. Steam from 70 pipe 8 enters at the top of said coil through a horizontal pipe 15, and a vertical pipe 16, the end of the lower coil being connected through pipes 17 and 18 with return pipe 12 to the boiler. 19 represents a blow-off 75 valve for removing any sediment that may accumulate in the coils, and 20 a closely fitting cover for the apparatus.

In operation, after a defective place in a tire or other article has been thoroughly 80 cleaned and built up in the usual manner where necessary, and otherwise properly prepared, it is placed in the circular chamber 21, when steam is generated in the boiler 7 to a pressure of 35 to 40 lbs. per square inch. 85 The steam passing from the boiler through pipes 8 and 15 to the coils 11 and 14 respectively, quickly generates 265° of heat within the chamber, bringing the article to the vulcanizing temperature, which is maintained until thorough vulcanization is completed. Any condensation of steam within the coils during the process of vulcanizing is returned to the boiler through pipes 17-18 and 12. 95

Having now set forth the object and nature of my invention and a form of apparatus embodying the same, and having described the construction, function, and mode of operation thereof, what I claim as new 100 and desire to secure by Letters Patent, is—

A vulcanizing apparatus comprising concentric inner and outer shells rising from the bottom thereof and secured thereto, a transverse partition located within the inner 105 shell and above the bottom, the intermediate

space between the shells and bottom being filled with a non-conductor of heat, a centrally located upstanding tube the height of the shells secured to the partition forming a circular chamber between the tube and the inner shell, a series of laterally disposed pipe coils adjacent and exteriorly surround-

ing the tube, a similarly disposed series of coils disposed interiorly of the inner shell adjacent thereto, and means for supplying steam of sufficient pressure to the coils to generate the desired heat in the chamber. 10

In testimony whereof I affix my signature.
JAMES E. RASOR.
